UNITED STATES PATENT OFFICE.

EDWARD P. COLE, OF CHICAGO, ILLINOIS.

MEANS FOR COUNTERBALANCING OVEN DOORS.

1,405,290.

Specification of Letters Patent. Patented Jan. 31, 1922.

Application filed August 9, 1919. Serial No. 316,477.

To all whom it may concern:

Be it known that I, EDWARD P. COLE, a citizen of the United States, residing at Chicago, in the county of Cook and State of Illinois, have invented certain new and useful Improvements in Means for Counterbalancing Oven Doors, of which the following is a specification.

The object of my invention is to provide a counterbalance for the oven door of a stove, or other door hinged at its bottom upon a horizontal axis, which shall be simple, strong, effective and suitable for the purpose for which it is designed, and which through its novel and original combination and arrangement of cooperating parts shall constitute an improvement over any devices of a similar character known to me. With this purpose in view I have designed and invented the counterbalancing device hereinafter described and which is illustrated in the accompanying drawings forming part of this specification, the essential elements of my invention being more particularly pointed out in the appended claims.

Of the drawing, Figure 1 is a perspective of a portion of a stove showing the oven door to which the weight is applied partly open; Fig. 2 is a vertical section of the stove walls immediately to the left of the counterbalancing mechanism, showing such mechanism in elevation; and Fig. 3 is a vertical section on the line 3—3 of Fig. 2.

The same reference characters indicate the same parts in all the figures of the drawing.

My invention in the specific embodiment shown in the drawing and now to be described is applied to a cooking stove 1 of ordinary construction, having an oven door 2 mounted upon trunnions 3 in the usual manner. One of these trunnions extends into the adjacent ash pit 4 of the stove, and to it, adjacent the side wall separating the ash pit and oven and within the ash pit opening, is secured a lever 5 extending rearwardly.

The rear end of this lever is arranged to slidably engage and cooperate with the hollowed or channeled lower side of a lever 6, pivoted at its front end upon the casing at a point a short distance above the axis of the oven door hinge and slightly to the rear thereof. The rear end of this lever carries a weight 7 of such size that with the described leverage arrangement it will over-

the latter and an intermediate position about half-way open, the weight exerting its most effective leverage through such arc, while between such intermediate point and open position of the door the latter will exert its greatest leverage and overbalance the weight. The result of this arrangement and relationship of the parts is that either in opening or closing the door it must be positively moved from its extreme position to and past the neutral point, and towards the end of its movement it will be assisted by the weight carried by the lever or the weight of the door, as the case may be, and when it comes to rest the door will be yieldingly maintained in open or closed position. The sliding engagement between the end of the lever 5 and the lever 6 is purposely made of such character as to provide a certain amount of frictional resistance which acts to cause a somewhat sluggish movement of the door and prevents a free acceleration of movement under the influence of the weight of the door, as the latter is closed or opened, which would result in slamming it to one or the other extreme position. Since the preponderance of weight on either side of the balancing point is small, the frictional resistance need not be great, and the door can be moved easily and will stop in open or closed position with a relatively slight shock or jar.

The lever 6 is formed with a shallow notch which engages the end of the lever 5 when the door is slightly ajar, say about one-eighth open. The notch is of such dimension, with respect to weight and proportions of the parts of the device, that when engaged as described, the weight 7 will not be able to move the door from a position of rest, but may be moved to cause disengagement by application of a slight degree of positive force to the door, and under the influence of momentum in a closing movement of the door the end of the lever 5 will slide past the notch without coming to rest in engaged position.

I claim:

1. In an oven or the like having a door hinged on a horizontal axis at its bottom, a lever rigidly secured to the door and extending rearwardly therefrom adjacent its hinge point, a second lever hinged adjacent the axis of the door and also extending rearwardly and equipped with a weight at its rear end, the rear end of said first mentioned lever slidably engaging said second lever

intermediate the axis of the latter and said weight.

2. In an oven or the like having a door hinged on a horizontal axis at its bottom, a lever rigidly secured to the door and extending rearwardly therefrom adjacent its hinge point, a second lever hinged adjacent the axis of the door and also extending rearwardly and equipped with a weight at its 10 rear end, the rear end of said first mentioned lever slidably engaging said second lever intermediate the axis of the latter and said weight, the weights of said door and weight being so proportioned that they will counter- 15 balance each other when the door is partly open and they will tend to close the door between such point and closed portion and tend to open such door between such point and fully opened position.
- 20 3. In an oven or the like having a door hinged on horizontal trunnions at its bottom, a lever rigidly secured to and projecting rearwardly from a trunnion, a second lever hinged adjacent and above said trunnion 25 and also extending rearwardly and equipped with a weight at its rear end, the rear end of said first mentioned lever slidably engaging

said second lever intermediate the axis of the latter and said weight.

4. In an oven or the like having a door hinged on a horizontal axis at its bottom, a lever rigidly secured to the door and extending rearwardly therefrom adjacent its hinge point, a second lever hinged adjacent the 30 axis of the door and also extending rearwardly and equipped with a weight at its rear end, the rear end of said first mentioned lever slidably and frictionally engaging said second lever intermediate the axis of the latter and said weight. 35

5. In an oven or the like having a door hinged on a horizontal axis at its bottom, a lever rigidly secured to the door and extending rearwardly therefrom adjacent its hinge point, a second lever hinged adjacent the 40 axis of the door and also extending rearwardly and equipped with a weight at its rear end, the rear end of said first mentioned lever slidably engaging said second lever intermediate the axis of the latter and said 45 weight and the engaging face of such second lever being formed with a shallow stop surface near its outer end. 50

EDWARD P. COLE.
